(57) **CLAIM**

The ornamental design for a bottle, as shown and described.

DESCRIPTION

FIG. 1 is a perspective view of a bottle according to my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown herein for illustrative purposes and which define the bounds of the claimed design form no part of the claimed design.

The broken lines showing the top of the neck and the bottom portion in FIG. 7 define the bounds and form no part of the claimed design.

The broken lines showing the cap represent environmental structure and form no part of the claimed design.
